[57] ABSTRACT

A fluid flow compressor includes means for arbitrarily obstructing part of the flow area of the compressor duct to improve the compressor efficiency at low flow velocities.

The means comprises a ring arranged in the duct and capable of being expanded in the manner of a circlip by a cam arrangement.

FLUID FLOW COMPRESSORS

This invention relates to fluid flow compressors and particularly to their use in gas turbine engines.

It is well known in the art of gas turbine engines to experience difficulty in first starting an engine.

A starter is provided for rotating the compressor up to the engine speed at which the engine becomes self-sustaining. The higher this self-sustaining speed is the more bulky and cumbersome is the starter.

The problem of starting a gas turbine engine at low rotational speeds originates in the design of the compressor.

The angles of incidence and attack of successive rotors and stators in a compressor are generally calculated on the basis of the gas velocity through them at the cruise r.p.m., this is considerably higher than the starting r.p.m. and it follows that the gas velocity through the blading at cruise is also considerably higher than at the starting r.p.m.

During starting the aforementioned angles of incidence and attack are incompatible with the low gas velocity associated with the low rotational speed of the compressor at the starting r.p.m. and the efficiency of the compressor suffers. In practice this means the engine will not start until the compressor can be rotated at a higher speed.

Several approaches have been followed in order to eliminate this problem. It is well known for example to design a compressor of which the blades of the early rotor and or stator stages can be rotated about their span axes, so as to alter the angles of incidence and attack. It is further known to bleed off a quantity of air after the first two or three rotor stages in this way increasing the mass flow through the early stages and boosting the gas velocity.

A third approach relies on blocking off part of the compressor duct to increase the gas velocity through the blades, in the past this has required complex and heavy arrangements to effectively obstruct parts of the duct.

According to the present invention a compressor for a gas turbine engine comprises radially inner and outer wall elements together defining an annular compressor duct, a substantially annular structure at least partly housed within one of the wall elements, said structure being split to form two ends and there being provided means operable on the structure to produce relative movement between the two ends to project a part of the structure into the duct for varying the cross-sectional area thereof.

A particular embodiment of the invention will now be described with reference to the accompanying drawings by way of example only, wherein

FIG. 1 shows a longitudinal section through a gas turbine engine having two spool axial flow compressor embodying the invention,

FIG. 2 shows the use of an expanded annular structure to obstruct the compressor duct of the gas turbine engine,

FIG. 3 is a detailed view of a longitudinal section through part of a compressor embodying the invention.

FIG. 4 shows an axial view of a particular annular structure and link operating means for expanding it in the manner of a circlip.

FIG. 5 is an enlarged drawing of the link operating means of FIG. 4.

Referring to FIG. 1 a gas turbine engine comprises a low pressure compressor 11, a high pressure compressor 12, a combustion system 13 and high pressure (h.p.) and low pressure (l.p.) turbines 14, 15 connected to their respective compressors by coaxial shafts 16 and 17. The h.p. and l.p. shafts 16 and 17 are each supported and constrained by two bearings respectively 18, 19 and 21, 22. At the entry to the h.p. compressor is provided an annular structure 23 which is completely contained in a cavity 24 (illustrated in FIG. 2) except during the starting of the engine when by means later explained its function is to obstruct part of the compressor duct 25. The compressor duct 25 is of annular form and is defined by radially inner and outer wall elements 30, 40 respectively.

Air delivered by the l.p. compressor 11 is received by the h.p. compressor 12. Substantially the same mass of air as delivered by the l.p. compressor will pass the annular structure 23 as would otherwise flow through the whole duct 25. This raises the gas velocity across the first few stages 21 of the h.p. compressor.

The cavity 24 forms an integral part of the structure 20 supporting the front bearing 18 of the h.p. shaft 16 the structure 20 also doubles as an inlet guide vane 26 for the h.p. compressor 12.

The detailed construction of FIG. 3 shows the front of the h.p. shaft 16 supported by a bearing 18.

Attached to the h.p. shaft 16 is the first stage rotor 27 of the h.p. compressor 12, immediately in front of the rotor 27 is the bearing support structure 37 which also houses the shaft 28. The shaft 28 is formed integrally with the cam 29. The annular structure 23 is split at one point to form two ends 42, 43. The two ends 42, 43 are attached to the two eyes 31, 32 respectively of the link 29 by pins 33 and trunnions 34. The link 29 is operable on the annular structure 23 to produce relative movement between the two ends 42, 43 to change the radius of the annular structure 23. When the radius of the annular structure is increased a part 44 of it will project into the duct 25 thus varying the cross-sectional area of the duct.

The increase and decrease of radius of the annular structure corresponding to relative movement of the two ends 42, 43 may be considered analogous to the operation of a circlip and is illustrated in FIGS. 4 and 5. The annular structure 23 is equipped with flanges 35 which restrict its radially outward movement by abutting with faces 36 on the bearing support 37.

In the event of the 'circlip' breaking it merely collapses harmlessly into the cavity 24 and is prevented from passing through the engine and thus causing subsequent damage by the flanges 35 being restricted by the faces 42 on the bearing support 37.

Rotation of the shaft 28 is effected by a lever 38 attached to the shaft 28 by a spline 41 working in the support structure, the rotation is illustrated by the arrow 39.

The mechanical advantage of the shaft 28 and link 29 system is such that only a small angular rotation of the shaft 28 is necessary to effect a substantial increase in the radius of the annular structure 23. The attachment of the cam 27 to the circlip 23 is more readily seen from this diagram.

The annular structure and link mechanism may of course be situated at other positions along the compressor duct 25, and may also be incorporated into the radially outer wall element 40. This latter embodiment

requires that the annular structure is contracted by the link in order to block off a part of the compressor duct.

It is sometimes desired to obstruct part of the cross-sectional flow area of a compressor duct at operating conditions other than starting. It may for example be useful in preventing surge phenomena which characteristically occur at certain rotational speeds typical of the particular engine, its installation and operating conditions. It may also be particularly desired to partially obstruct a sector of the cross-sectional flow area of a compressor duct and it will be appreciated that the invention may be applied to the above situations by mounting it in a position other than its normal position concentric with the axis of the compressor duct.

The annular structure can be used on its own or in conjunction with other effective procedures, for boosting the gas velocity through a compressor.

I claim:

1. A compressor for a gas turbine engine comprising radially inner and outer annular wall elements together defining an annular compressor duct, a substantially

annular structure at least partly housed within one of the wall elements, said structure being split to form two ends, and there being provided means operable on the structure to produce relative movements between the two ends to project a part of the structure into the duct for varying the cross-sectional area thereof.

2. A compressor according to claim 1, wherein the substantially annular structure is mounted concentrically with respect to the compressor duct.

10 3. A compressor according to claim 1, wherein the substantially annular structure is a circlip.

4. A compressor according to claim 1, wherein the substantially annular structure is provided with a flange arranged to abut one of the wall elements of the duct to restrict the radial movement of the structure.

15 5. A compressor according to claim 1, wherein the means operable on the structure to produce relative movement between the two ends thereof comprises a link, means for connecting the link to the ends of the structure and means for rotating the link.
